Atty.

UNITED STATES PATENT OFFICE.

WILLIAM ANTHONY, OF CLYDE, OHIO.

BATTERY-METER.

1,262,000.

Specification of Letters Patent. Patented Apr. 9, 1918.

Application filed June 4, 1917. Serial No. 172,721.

To all whom it may concern:

Be it known that I, WILLIAM ANTHONY, a citizen of the United States, residing at Clyde, in the county of Sandusky and State 5 of Ohio, have invented certain new and useful Improvements in Battery - Meters, of which the following is a specification.

This invention relates to instruments used for measuring the energy or electromotive 10 force of batteries and it has particular reference to the construction of meters of the permanent magnet type and which is adaptable for voltmeters, ammeters, or volt-ammeters. The object of the invention is to provide a 15 construction that is efficient and reliable for the intended purpose of the instrument; that is durable; and that is economical to manufacture. With this object in view the invention consists in the novel construction, arrangement and combination of parts as fully 20 described in the following specification and pointed out definitely in the annexed claims, reference being had to the accompanying drawings which form a part of the specification and in which similar characters of 25 reference are employed to designate similar parts.

In the drawings Figure 1 is a face view of a voltmeter embodying the improvements.

Fig. 2 is an elevation with the casing in 30 central vertical section, or on line 2—2, Fig. 1.

Fig. 3 is a view of the face plate and attached elements taken at right angles to that 35 shown in Fig. 2.

Fig. 4 is a view of the base member, solenoid support, face plate and pivot staff assembled and detached from the other elements.

Fig. 5 is a plan view of the base member 40 showing threaded attachment bosses in section.

Fig. 6 is a plan view of the face plate.

Fig. 7 is an underside view of said face 45 plate and the elements that are attached thereto.

Fig. 8 is a view of the permanent magnet.

Fig. 9 is a fragmentary section of the face 50 plate, solenoid support and pivot staff, and Fig. 10 is an underside view of the supporting bracket.

An important feature of the present in-

vention is the construction being almost entirely die work. The front or face plate 1 is made of non-magnetic metal and has the dial 55 2 mounted thereon. A portion 1^a of the face plate is struck up above the dial. This arrangement allows the moving element or indicating finger 3 to be made straight and to operate in a parallel plane with the dial 2 60 for its entire length, it also provides a clearance chamber 1^b in which the balance weight 3^a is free to oscillate in a plane with the index finger 3. A slot 1^c is provided for the projection of the finger 3 and the arc of oscillation of said finger is limited by the extremities of said slot.

The pivot staff 4 on which the index finger 3 is fixed is mounted in point bearings 1^d in the member 1^a and 5^a of the supporting 70 bracket 5. The bracket 5 is of non-magnetic metal and not only provides a bearing for the pivot staff 4, but also furnishes a support for the solenoids 6, being adaptable for the support of one or more solenoids, there being 75 two in the embodiment as shown.

The bracket 5 is first formed with the lower member as shown by dotted line in Fig. 9 and is attached to the member 1 by punch rivets 1^e which are integral with 80 member 1. In assembling, the pivot staff 4 is placed in position between member 1^a and bracket 5, one terminal point of the staff 4 being seated in the bearing 1^d. The bracket is held firmly in suitable jaws provided 85 therefor, and the lower member of bracket 5 is up-set or crimped to seat the opposite terminal point of staff 4 in the bearing 5^a, the crimping process being such as to give the proper adjustment to the pivot staff. This 90 crimping process maintains the journals or female pivot impressions in a rigid position that is not disturbed by vibration.

The base member 7 is formed with lugs 7^a provided with right angle members 7^b for 95 supporting the face plate 1, said face plate being attached by screws 8 threaded into the members 7^b. The base member 7 is also provided with lugs 7^c having internally threaded bosses 7^d thereon to accommodate 100 screws for attachment of the casing 9 which incloses the working elements and is provided with a glass cover 10.

The coils or solenoids 6 are mounted on

the arms 5^b which are preferably integral with the bracket 5. A permanent magnet 11 is adjustably attached to the face plate 1 in the following described manner:—Two 5 lugs 1^f and 1^g are formed integral with the member 1, being cut and turned inward therefrom. The member 11^a of the magnet 11 is an arc having the staff pivotal point as a center, said member 11^a being adapted 10 for confinement between the lugs 1^f and 1^g, and being held therein by a clamp bolt 12. The magnet 11 is thus made angularly adjustable, and the ends or poles 11^b and 11^c of said magnet being angular, relative to the 15 body of the magnet, allows a fine adjustment for causing the soft iron vane 4^a on the pivot staff to assume a position in relation to the solenoids that is most conducive to a uniformly divided scale on the dial which indicates the voltage by the registration of the 20 index finger 3 with said dial.

Electrical connections are made between the solenoids 6 and the binding posts 13 and 13^a through conducting wires, not shown but 5 connecting said solenoids with members 14 and 14^a, said members 14 and 14^a being attached to the base member 7 and connected with the binding posts 13 and 13^a, and being insulated from the base by insulating 10 members 15 and 16.

As the functions of the coöperating elements as embodied in the improved meter are common to meters of this character, it is not deemed necessary or expedient to encumber the specification with a description 5 of the operation, owing to the fact that the present invention has reference to the novel construction, arrangement and combination of the elements whereby the required functions 10 are performed. The said novel construction providing a durable, convenient and accurate instrument that can be used either as an ammeter, a voltmeter, or both, and which is particularly economical to 15 manufacture.

Having fully described my invention what I claim and desire to secure by Letters Patent is:—

1. A face plate for meters, and a dial 50 mounted on the exterior of said plate, said plate having a raised portion pressed therein beyond the plane of the dial and having a slot cut through the pressed up portion in a parallel plane with the dial.

55 2. In a battery meter, a face plate on which the meter dial is mounted, said plate having a portion thereof formed up beyond the plane of the dial and provided with a slot in parallel plane with the dial, a permanent magnet attached to the underside of 60 the face plate, a solenoid supporting bracket attached to the underside of said face plate, a pivot staff carrying an indicating finger and a magnetic attraction vane mount-

ed in said supporting bracket and formed 65 up portion of the face plate, the said indicating finger projecting through the slot in a parallel plane with the dial.

3. A base member for a battery meter, comprising a supporting body provided with 70 an annular rim having integral radial bosses formed thereon for attachment of the meter casing, and having integral right angularly disposed lugs for attachment of the meter face plate.

4. A base member for a battery meter, comprising a supporting body provided with an annular rim having integral radial bosses formed thereon for attachment of the meter casing, and having integral right angularly 80 disposed lugs for attachment of the meter face plate, and having binding post connections attached thereto and insulated therefrom.

5. In a battery meter, a case; a base member secured therein; a face plate on which the dial is mounted attached to said base member, a portion of said face plate being formed up beyond the plane of the dial; a solenoid; a magnet; an oscillating indicating-finger; and binding post connections; said base member adapted to support the binding post connections, and said face plate adapted to support all the other elements, the indicating-finger projecting through the 95 formed up portion of said face plate.

6. In a battery meter a face plate having a portion thereof formed up beyond the plane of the body of the plate and provided with a point bearing; a bracket attached to 100 the underside of said face plate and provided with a crimped portion; an oscillating pointer staff journaled in said crimped portion and the point bearing in the face plate; and coils supported by said bracket.

105 7. In a battery meter a face plate having a portion thereof formed up beyond the plane of the body of the plate and provided with a point bearing; a bracket attached to the underside of said face plate and provided with a crimped portion; an oscillating pointer staff journaled in said crimped portion and the point bearing in the face plate; coils supported by said bracket; integral lugs formed on the underside of the face 110 plate; and a magnet supported by said lugs.

8. In a battery meter a face plate having a portion thereof formed up beyond the plane of the body of the plate and provided with a point bearing; a bracket attached to 115 the underside of said face plate by integral punch rivets and provided with a crimped portion; an oscillating pointer staff journaled in said crimped portion and the point bearing in the face plate; and solenoids supported by said bracket.

9. In a battery meter a face plate having a portion thereof formed up beyond the

plane of the body of the plate and provided with a slot and a point bearing; a bracket attached to the underside of said face plate and provided with a crimped portion, said bracket supporting an oscillating staff having an indicating finger attached thereto and journaled in the point bearing in the formed

up portion of the face plate and in the crimped portion of the bracket, the indicating finger projecting through the slot in 10 said plate its oscillating movement being limited by said slot.

In testimony whereof I affix my signature.
WILLIAM ANTHONY.
